UNITED STATES PATENT OFFICE.

JOSEPH H. MILLS, OF RICHMOND, INDIANA.

SELF-COMPENSATING COT.

1,308,187.

Specification of Letters Patent.

Patented July 1, 1919.

Application filed October 10, 1918. Serial No. 257,577.

To all whom it may concern:

Be it known that I, JOSEPH H. MILLS, a citizen of the United States, residing in the city of Richmond, in the county of Wayne 5 and State of Indiana, have invented a new and useful construction which I denominate as a Self-Compensating Cot, of which the following is a full, clear, and accurate specification and exposition, the same being such 10 as will enable others to appreciate and construct the same with exactitude.

The object of my present invention, broadly speaking, is to provide a self-compensating cot construction which will be 15 strong and durable in practice, light in weight, comfortable in use, easily packed into a small compass of space for transportation or storage, and which can be manufactured at a comparatively low price.

More specifically stated, my object is to provide a self-compensating cot construction which comprises a spring frame, in which the central element or body is formed preferably of fabric, such for instance as canvas, or other flexible material, which is stretched in the frame and carried thereby, and having particularly novel means whereby the fabric will not become baggy or flabby after being used, but will retain its 25 tension under excessive weight superimposed thereon, but at the same time will adjust itself to one's body whereby it will be comfortable to lie upon but will immediately retrieve itself and rebound to its normal taut position when the weight is removed therefrom.

Other minor and specific objects and advantages of the invention will suggest themselves in the course of the following description, and that which is new and useful will be correlated in the appended claims forming a part of the specification.

The preferred means for the construction and the assembly of my invention in a practical and mechanical manner is shown in the accompanying drawings, in which—Figure 1 is a side elevation of the complete construction as it would appear ready for use.

Fig. 2 is a detail cross section, as taken 50 on the line 2—2 of Fig. 4. Fig. 3 is a detail cross section, as taken on the line 3—3 of Fig. 6. Fig. 4 is a detail bottom plan of

one corner portion of the cot, with the leg of that corner removed, and as taken, for instance, on the line 4—4 of Fig. 1. Fig. 5 55 is a bottom plan of one corner portion, partly in section as taken on the line 5—5 of Fig. 1. Fig. 6 is an end elevation of the invention. Fig. 7 is a cross section, as taken on the line 7—7 of Fig. 1. Fig. 8 is a perspective view of the upper portion of one of the legs. And Fig. 9 is a detail cross section of a modified form for the construction of the side rails.

Similar indices denote like parts throughout the several views.

In order that the construction, the operation, and the advantages of the invention may be more fully understood and appreciated, I will now take up a detail description 70 thereof, in which I will set forth the several features thereof as fully and as comprehensively as I may.

Referring now to the drawings in detail: The invention comprises a frame formed 75 by side-rails and end rails, with the central element or fabric stretched between said rails, and retained taut as hereinafter set forth.

Simply for convenience of description I 80 will hereinafter refer to the right-hand side and the left-hand side; also the head, which is the portion to the right in Fig. 1, as the "head", while the portion to the left in Fig. 1 will be referred to as the "foot", but these 85 terms are arbitrary, for in practice it will make no difference which end of the cot is employed as the head or the foot.

The right-hand side rail is composed of the lower rail member 1 and the upper rail 90 member 2. Formed in the lower or contact face of the member 2 is a channel 3, which extends longitudinally throughout the length thereof, and in the channel 3 is slidably located the strip 4. The members 1 and 2 are 95 adapted to be secured together by a plurality of screws 5, or otherwise, in such manner as to form the equivalent of a solid or integral membered rail having a closed channel therein, with the strip 4 slideable in said 100 channel. The under face of the member 2, from the channel 3 centerward, is cut slightly away to provide a very narrow mouth, as indicated at 6 in Fig. 7.

Identical with the above is the left-hand side rail, which is composed of the lower rail member 10 and the upper rail member 12. Formed in the lower or contact face of the member 12 is a channel 13 which extends longitudinally thereof throughout the entire length of the member 12, and in the channel 13 slidably located the strip 14. The members 10 and 12 are adapted to be secured together by a plurality of screws 15, or other means, such as to form the equivalent of a solid or integral membered rail having a closed channel therein with the strip 14 slideable in said channel. The under face of the member 12, from the channel 13 centerward, is cut away slightly to provide a very narrow mouth, as indicated at 16 in Fig. 7.

The head rail comprises an outer or cap member 7 having a tongue 7^a on each end thereof which tongues are adapted to fit in mortises in the ends of the side rails, said mortises being formed by notches cut equally in the upper and the lower members of the side rails, as indicated in Fig. 1. The head rail also includes the removable stretcher bar 8, with one edge thereof adapted to contact with the member 7 to which it may be detachably secured by a plurality of screws 9. The ends of the bar 8 are adapted to fit in notches formed in the inner edges of the head-end portions of the members 1 and 10, whereby the ends of the bar 8 will contact with the members 2 and 12, with the outermost edge in contact with the member 7, as shown in Fig. 4.

The lower portion of the innermost edges of said notches for the member 8 are beveled, as at 17 in Fig. 2, but still providing a small shoulder 18 at the base of said bevels, also as shown in Fig. 2.

The said bevels are provided for the purpose of facilitating the insertion and the removal of the bar 8, as will hereinafter be explained. The bar 8 is located even at its lower edge with the member 7, but is substantially only one-half of the height thereof.

The foot rail comprises an outer or cap member 19 having a tongue 19^a on each end thereof, which tongues are adapted to fit in mortises formed in the ends of the side rails, said mortises being formed by notches cut equally in the upper and the lower members of the side rails, as indicated in Fig. 6. The foot rail also includes the stationary bar 20, with one edge thereof adapted to contact with the member 19, to which it is secured by a plurality of screws 21, and it extends between the members 1 and 10 with its ends notched into the members 1 and 10. The bar 20 is located flush at its lower edge with the member 19 but it is substantially only one-half the height thereof, substantially as shown.

The central element or body consists of

a section of canvas material 22, which is 65 preferably a fabric such as canvas cloth, although it may be other suitable material as desired, but for convenience of description this element will, hereinafter, be referred to simply as "canvas", it being understood that 70 it is not to be limited thereby. The side edges of the canvas are secured, as by tacks 23 or other means, to the upper surfaces of the strips 4 and 14, being adapted to be stretched tightly therebetween. The foot end 75 of the canvas is rigidly secured between the member 19 and the bar 20, while the head end of the canvas is secured to the bar 8, and it is wrapped therearound, and the bar 8 is adapted to be turned in order to stretch 80 the canvas, when desired, to the desired tension.

Supports or legs 24, 25, 26 and 27, are provided, one for each corner of said construction, each being adapted to be detachably 85 secured by a plurality of screws 28 which extend upward through apertures 29 in the rims 30 of the legs into apertures 31 of the rail members 1 and 10, as indicated in the drawings. 90

Assembly.

The canvas material is first secured at its edges to the strips 4 and 14, as shown, after which said strips are placed in their respective 95 channels 3 and 13. The members 1 and 10 are then secured to the respective members 2 and 12, after which the members 7 and 19 are placed in position which will space the side rails in such manner that the canvas 100 will be stretched tight. The foot portion of the canvas is then placed in position and the bar 20 is then brought to place to secure the canvas between the bar 20 and the member 19, the bar 20 being then permanently secured in place as shown.

Finally the head end portion of the canvas is secured to the bar 8 after which said bar 8 is turned until all of the slack in the canvas is taken up, after which the bar 8 is 110 forced down toward the member 7 until it contacts therewith, the ends of the bar 8 sliding on the bevel edges 17 until finally the bar 8 comes into position, as in Fig. 2, in contact with the shoulders 18. After the above 115 the bar 8 is secured to the member 7 by a plurality of screws 9. On account of the beveled faces 17 it is evident that the operation of inserting or removing the bar 8 under tension will be greatly facilitated. 120

In the event that the canvas should become slack, through long usage, it is evident that one may loosen the screws 9, after which the bar 8 may be turned to take up the slack, and then when the bar 8 is replaced as before the canvas will have its original tightness. 125

It should be observed that the strips 4 and

14 are not as long as are the channels 3 and 13 in which they are located, thereby permitting them to move endwise under strain, in fact said strips 4 and 14 may each be 5 formed of a plurality of separate lengths, but I have found from tests which have been made that single length strips will permit the required self compensation.

As the weight is applied to the canvas, 10 after being secured as stated, it is found that the weight will be equally distributed so that every thread of the material throughout the whole extent thereof will be caused to carry its proportion of the load, thereby accomplishing at least three very desirable 15 results: permitting a given grade of canvas to carry a much greater load without damage thereto; causing the canvas after being subjected to a load to instantly retrieve or regain its former shape and tautness without 20 wrinkles or bagginess; and providing a cot which will give the highest degree of comfort to the user. And an alternative result is, that a poorer grade of canvas may be employed, which would be equal to a better 25 grade of canvas when used in the ordinary construction of cots.

When considerable weight is placed on the cot it is evident that the side rails, which 30 are resilient, may spring or bow slightly toward each other and downward, which manifestly will act in the nature of springs, thereby adding to the comfort of the person lying on the cot, but said rails will immediately 35 regain their normal shape when the weight is removed.

Also, it should be observed, that as the legs are well braced, as shown, and are rigid with the frame of the cot, their lower ends 40 may spread slightly apart when weight is applied to the cot.

From the above it will be evident that the 45 sliding means for the side edges of the fabric, the resiliency of the side-bars, and the rigidity of the legs, will form a combination which will contribute to the efficiency of the cot as an entirety.

It is to be understood that the end rails 50 may be identical with each other in construction, that is the fabric may be permanently or adjustably secured at each end, if so desired, without affecting the principles of this invention. Also the side rails may each be of a single member, in place of two-part 55 member, with the channels formed therethrough.

Modified form.

As shown in Fig. 9 the channel 3 may be 60 formed in the rail 1, with the fabric 22 secured to the strip 4 therein, from which the fabric extends outward between the members 1 and 2, and then over the member 2, the inner upper edge of the member 2 being 65 rounded, as at 2^a, in order to eliminate the

sharp corner for the fabric to bend over, otherwise the modification will be the same as that first described.

I desire that it be understood that various changes may be made in the several details 70 of construction, from that herein shown and described, without departing from the spirit of my invention and without sacrificing any of the advantages thereof.

Having now fully shown and described 75 my invention, what I claim and desire to secure by Letters Patent of the United States, is—

1. A self compensating cot construction, comprising in combination, a pair of two-part side rails each having a channel therein extending longitudinally thereof with a mouth opening from said channels through the inner edges of the rails, a strip located slidably in each of said channels, a fabric 80 element having its longer edges secured to the respective strips and passing loosely through said mouths without frictional contact with the members of the rails, and rails spacing said side rails apart and retaining 85 the fabric element tight therebetween, means for permanently securing one end of the fabric to one of said end rails, and means for adjustably securing the other end of said fabric. 90

2. A self compensating cot construction comprising, a frame composed of two side-rails and end rails interlocked and rigidly connected with the ends of the side rails, a fabric element stretched between said rails, 100 each side rail being composed of an upper and a lower portion secured together with a channel formed between the two portions extending longitudinally thereof, a strip located in each of said channels and slideable 105 endwise therein and being of less length than the channel in which it is located, means for securing the side edges of the fabric element to said strip after passing through the mouths formed through the opposing inner 110 faces of the side rails, means for securing one end of the fabric to one of the end rails, a removable bar located near the other end rail and to which the other end of the fabric element is secured, and means for removably 115 securing said bar in position after it has been turned to obtain proper tension of the fabric element.

3. A self compensating cot construction comprising in combination, two spaced apart 120 side rails each including an upper and a lower member rigidly secured together with a channel formed in the central portion between the members and having a mouth formed between the members on one side of said channel, a strip slideable endwise in the channel of each side rail, a fabric having its side portions disposed through said mouths in the side rails with its side edges secured to said strips, an end rail connecting 125 130

the side rails at one end and to which one end of the fabric is permanently secured, an end rail connecting the other ends of the side rail, a removable bar to which the other 5 end of the fabric is secured and upon which the fabric is wound to secure endwise tension thereof, and means for locking said bar to retain the endwise tension of the fabric, all substantially as shown and described.

In testimony whereof I have hereunto 10 subscribed my name to this specification in the presence of two subscribing witnesses.

JOSEPH H. MILLS.
